UNITED STATES PATENT OFFICE.

OSCAR H. HEINIG, OF CHICAGO, ILLINOIS.

SPOOL AND THE LIKE.

1,384,562.

Specification of Letters Patent. Patented July 12, 1921.

Application filed March 18, 1920. Serial No. 366,889.

To all whom it may concern:

Be it known that I, OSCAR H. HEINIG, a citizen of the United States, residing at Chicago, in the county of Cook and State of Illinois, have invented certain new and useful Improvements in Spools and the like, of which the following is a specification.

The spool to which the present invention relates is particularly intended for winding electric wire and the like, although manifestly spools embodying the features of the present invention may be used for many other purposes.

One feature of the present invention has reference to the construction of spools having their body portions made of wood or other grained material; and in this connection one of the objects of the invention is to provide a construction of spool such that when made from wood or other grained material it may be made with a minimum amount of wastage. This feature of the invention will be understood when it is considered that in the case of a spool cut or turned from a solid block of wood it is necessary to use a block whose original dimensions in the three principal directions are at least equal to the ultimate dimensions of the completed spool. In this connection, one of the objects of the invention is to provide a built up construction of such design and arrangement that the various parts or sections thereof may each be cut with a minimum percentage of wastage of raw material.

Another feature of the invention relates to the provision, in built-up spools, of a metallic sheeting or covering for certain portions thereof.

Other objects and uses of the invention will appear from a detailed description of the same, which consists in the features of construction and combinations of parts hereinafter described and claimed.

In the drawings:

Figure 1 shows a longitudinal section through a spool embodying the features of the present invention, the inside faces of the end flanges being surfaced or sheeted with metal. Fig. 1 may be considered as a section taken on line 1—1 of Fig. 2 looking in the direction of the arrows;

Fig. 2 shows an end view of the spool of Fig. 1;

Fig. 3 shows an end view of the spindle used in building up the spool;

Fig. 4 shows an edge view of one of the

facing sheets before the edge flange thereof has been turned down;

Fig. 5 is an inside face view corresponding to Fig. 4;

Fig. 6 is a side elevation of one of the hub spindles showing the longitudinally extending grain thereof;

Fig. 7 is a face view of one of the flange disks showing the cross grain thereof; and

Fig. 8 is a fragmentary view corresponding to Fig. 1, with the exception that it shows a modified type of construction.

Referring first to Fig. 1, there will be observed the central spindle section 10. This is ordinarily of cylindrical form, being provided with a longitudinal perforation 11. The end flanges are designated in their entirety by the numerals 12 and 13 respectively. I will first describe the construction of one of these end flanges of the type shown in Figs. 1 and 2, and will afterward describe the modified construction shown in Fig. 8.

Each of the end flanges includes a flat relatively thin disk 14 of wood or the like; and when grained material, such as wood, is used, it is preferred that the disks 14 be cut out of a narrow board of a thickness substantially equal to the thickness of the disks, so as to cut said disks with a minimum of wastage of material.

The central portion of each disk 14 is provided with a circular opening 15 into which seats a hub 16. Each of the hubs 16 has a central neck portion 17, generally of tapered form, which is adapted to seat snugly into the end of the longitudinally extending passage 11 of the spindle 10. Each hub is also provided in some cases with an outwardly extending flange 18 of diameter 95 to seat snugly within the opening 15 of the corresponding disk 14; but whether the flange 18 be provided or not, the opening 15 should be of such a size as to snugly receive the end portion of the hub 16.

In those cases in which the hubs 16 are made of wood or other grained material, the grain thereof should preferably run in the direction of the axis of the completed spool, this fact being clearly illustrated in Fig. 6, so that the hubs may be turned from blocks of minimum size and with a minimum wastage of raw material.

It will thus be observed that by making the hubs and flanges or disks from two pieces it is possible to greatly economize in the amount of raw material necessary, which is

a very important item owing to the rapidly diminishing supply of suitable lumber.

The necks 17, if desired, may be pinned to the spindle 10 by the transversely extending pins 19, but this is optional with the designer. Ordinarily a pair of openings 20 and 21 will be provided in one of the end flanges for the accommodation of the end portions of the wire or material intended to be wound on the spool; and if desired a hole 20^a may be provided in the other end flange for a like purpose.

It is to be observed, from an examination particularly of Fig. 1, that the end portions 15 of the spindle 10 project slightly into the flange portions 12 and 13, so that there is a certain amount of overhang established. A convenient way of bringing about this result is to form the openings 15 of substantially the same diameter as the spindle 10, and in such case make the flanges 18 slightly thinner than the disks 14, so that when the outer surfaces of the hubs and their disks are brought flush together, as shown in Fig. 1, a shoulder will be established for the accommodation of the corresponding end portion of the spindle 10.

In many cases it will be desirable to provide a metallic facing 20^b on the inner face of the disks 14; and when the same is used it may be made of the form shown in detail in Figs. 4 and 5. As therein illustrated, its central portion 23 is slightly depressed to correspond with the shoulder aforementioned, and its inner peripheral portion is inturned to provide a series of lugs or the like 24. These lugs may be driven into the grain on the end of the spindle 10 but ordinarily a groove 25^a will first be formed in the end of the spindle so as to guide the lugs and insure that they will all come to a proper seat within the grain.

The flange portion 24 of the sheeting 22 may be inturned or beaded over against the outer face of the corresponding disk 14, as shown in Figs. 1 and 2, and when this is done it will generally be desirable to provide a peripheral groove or shoulder in the disk, so that the completed spool will present a flush 50 outside or end surface, as shown in Fig. 1.

If it be desired to sheathe the outside ends of the completed spool, this may be done by the use of end plates 25 such as shown in Fig. 8, which will be held in place by the bead 55 or flange 24 formed as just above explained.

While I have herein shown and described only certain embodiments of my present invention, still I do not limit myself to the same except as I may do so in the claims.

60 I claim:

1. As a new article of manufacture, a spool comprising a cylindrical wooden hollow spindle having grain extending in an axial direction, and an end piece for each end thereof, each end piece including a circular

wooden hub having a tapered neck of size suitable to enter the spindle with a driving fit and having an outside flange, a circular relatively thin wooden disk having an inner opening of size to receive said flange, the grain of the hub extending in an axial direction with respect to the spindle, and the grain of the disk extending at right angles to the grain of the hub, and a sheet metal facing for the inner face of each of said end pieces comprising a circular sheet metal disk of size appropriate to face the inner face of the end piece and having a peripheral outwardly extending flange adapted to overlie the edge of the disk, the edge of said flange being inturned against the extreme edge portion of the outer face of the disk, and the inner portion of each of said sheet metal faces having a series of inwardly projecting prongs adapted to engage the grain of the end portion of the spindle, substantially as described.

2. As a new article of manufacture, a spool comprising a cylindrical wooden hollow spindle having grain extending in an axial direction, and an end piece for each end thereof, each end piece including a circular wooden hub having a neck of size suitable to enter the spindle and having an outstanding flange, a circular relatively thin wooden disk having an inner opening of size to receive said flange, the grain of the hub extending in an axial direction with respect to the spindle, and the grain of the disk extending at right angles to the grain of the hub, and a sheet metal facing for the inner face of each of said end pieces comprising a circular sheet metal disk of size appropriate to face the inner face of the end piece and having a peripheral outwardly extending flange adapted to overlie the edge of the disk, the edges of said flange being inturned against the extreme edge portion of the outer face of the disk, and the inner portion of each of said sheet metal faces having a series of inwardly projecting prongs adapted to engage the grain of the end portion of the spindle, substantially as described.

3. As a new article of manufacture, a spool comprising a cylindrical wooden hollow spindle having grain extending in an axial direction, and an end piece for each end thereof, each end piece including a circular wooden hub having a neck of size suitable to enter the spindle and having an outside flange, a circular relatively thin wooden disk having an inner opening of size to receive said hub, the grain of the hub extending in an axial direction with respect to the spindle, and the grain of the disk extending at right angles to the grain of the hub, and a sheet metal facing for the inner face of each of said end pieces comprising a circular sheet metal disk of size appropriate to face the inner face of the end piece and having a

peripheral outwardly extending flange adapted to overlie the edge of the disk, and the inner portion of each of said sheet metal faces having a series of inwardly projecting 5 prongs adapted to engage the grain of the end portion of the spindle, substantially as described.

4. As a new article of manufacture, a spool comprising a cylindrical wooden 10 low spindle having grain extending in an axial direction, and an end piece for each end thereof, each end piece including a circular wooden hub having a neck of size suitable to enter the spindle, a circular relatively thin 15 wooden disk having an inner opening of size to receive said hub, the grain of the hub ex-

tending in an axial direction with respect to the spindle, and the grain of the disk extending at right angles to the grain of the hub, and a sheet metal facing for the inner face of 20 each of said end pieces comprising a circular sheet metal disk of size appropriate to face the inner face of the end piece and having a peripheral outwardly extending flange 25 adapted to overlie the edge of the disk, and the inner portion of each of said sheet metal faces having a series of inwardly projecting prongs adapted to engage the grain of the end portion of the spindle, substantially as described.

OSCAR H. HEINIG.
